UNITED STATES PATENT OFFICE

RUDOLPH BECKER, OF NORTH PLAINFIELD, NEW JERSEY, ASSIGNOR TO THE SINGER MANUFACTURING COMPANY, OF ELIZABETH, NEW JERSEY, A CORPORATION OF NEW JERSEY

LOOP SPREADER FOR SEWING MACHINES

Application filed December 14, 1928. Serial No. 326,132.

This invention relates to sewing machines, more particularly of the straw-braid sewing type having hook and eye-pointed needles disposed below the throat-plate, and has for an object to improve the stitch-forming mechanism of a machine of this type so that it will not skip stitches under the varying sewing conditions met with in practice. More specifically, the invention has for an object to improve the stitch-forming mechanism so that irregular seams or curved seams of short radius may be sewn without skipped stitches.

To the attainment of the ends in view, there is provided on the same side of the work at which the needles are mounted, a loop-spreader adapted to enter the thread-loop on the hook-needle and spread such loop for certain entry by the eye-pointed needle. Preferably, the loop-spreader has an inverted V-shaped loop-spreading portion which is preferably disposed between the needles with its point extending in the direction of reciprocation of said needles. It is also preferred to so mount the loop-spreader that it may be moved in the direction of reciprocation of the needles; the movement being such as to cause the spreader to rise with and somewhat faster than the needles, thereby entering and spreading the thread-loop on the hook-needle and serving additionally to prevent premature shedding of the loop by the hook-needle. When the spreading of the loop has been accomplished, the spreader dwells while the needles continue their upward motion; the eye-pointed needle entering the spread loop and the hook-needle shedding such loop which is tightened in the usual manner.

It is further preferred to provide the machine with a throat-plate having a needle-hole or slot closed at its sides and rear, to control the slant of the threads from the needles to the work when sewing long stitches, and to prevent the threads from being unduly drawn to one side of the plane of the needles when sewing abrupt corners or curved seams of short radius.

In the accompanying drawings Fig. 1 is a fragmentary end elevation of a straw-

braid sewing machine embodying the invention; the needles and loop-spreader being at the lower limits of their respective strokes. Fig. 2 is a fragmentary front elevation of the machine with the parts in the same relative positions shown in Fig. 1. Figs. 3 and 4 are views similar to Figs. 1 and 2, respectively, with the needles rising and the loop-spreader at its position of dwell at the upper limit of its stroke. Fig. 5 is a disassembled perspective view of the loop-spreader and its carrier. Fig. 6 is a bottom view of the bed-cover-plate on which the loop-spreader is pivotally mounted. Figs. 7, 8 and 9 are, respectively, side, front and top-plan views of the needles and spreader at the period of the cycle when the needle-points have descended clear of the work and the feed of the work has commenced. Figs. 10, 11 and 12 are views similar to Figs. 7, 8 and 9, respectively, with the needles and spreader all the way down and the feed of the work continuing; the spreader point being straddled by the thread-loop on the hook-needle. Figs. 13, 14 and 15 are similar views with the needles rising and the spreader at the upper limit of its stroke; the thread-loop being held in the barb of the hook-needle and fully spread for entry by the eye-pointed needle. Fig. 16 is a plan view of the loop-spreader and its carrier in its relation with the needles and throat-plate of the machine, and Fig. 17 is a perspective view of the loop-spreader removed from its carrier.

For the purpose of the present disclosure, the invention is shown as embodied in a sewing machine having substantially the constructive features set forth in the patent to R. Becker, No. 1,429,399 of Sept. 19, 1922. Such a machine comprises a bed 1, overhanging head 2, presser-foot 3, feed-dog 4, bed-cover-plate 5, and throat-plate 6. Slidably mounted in the bed 1 is the reciprocating needle-bar 7 having at its upper end the offset head 8 carrying the eye-pointed needle 9 and hook-needle 10, with which the loopers 11, 12 cooperate in the usual manner to form stitches.

The needle-bar is actuated by the link-con-

nection 13 with the slide-block 14 embraced in the fork of the lever 15 fulcrumed at 16 on the bed 1. The lever 15 is given rocking movements by the pitman 17 which embraces the eccentric 18 on the main-shaft 19. The position of the slide-block 14 in the fork of the lever 15 is controlled by the thickness of the work under the presser-foot 3, by connections such as disclosed in the Becker patent referred to, whereby the needles 9, 10 are caused to rise to a constant height above the upper surface of the work, regardless of variations in work-thickness. As the foregoing features are common to sewing machines of the straw-braid type and are well known to those skilled in the art, further discussion thereof is deemed unnecessary.

In the operation of a sewing machine of the type in question, when the needles are above the work, the looper-mechanism seizes a thread-loop from the eye-pointed needle 9 and deposits it in the barb of the hook-needle 10. When the needles descend, the hook-needle draws this thread-loop down through the work. When the work is fed, the limbs of this thread-loop are carried rearwardly over the eye-pointed needle which enters such loop in its next ascent. The thread-triangle formed by the loop on the hook-needle has a very short base, constituted by the portion of the loop lying in the barb of the hook-needle, and long sloping sides leading from the base at a rearward and upward slant to the last stitch. In other words, the spread of the loop, which is determined solely by the width of the barb of the hook-needle, is so narrow that there is danger that such loop will not be entered by the eye-pointed needle, thus resulting in a skipped stitch. The danger is greatly increased in sewing irregular or curved seams or whenever, in the feed of the work, the last formed stitch is carried to one side of the vertical plane of the needles, since such movement of the last stitch tends to shift the thread-loop triangle to one side of the path of the eye-pointed needle.

To avoid the danger referred to and make the machine more certain in its operation, there is provided a loop-spreader 20 in the form of a flat blade having an inverted V-shaped point 21 disposed between the needles 9, 10 with the plane of the blade 20 and point 21 transverse to the plane of the needles; the point 21 extending upwardly or in the same direction as the points of the needles. The point 21 is disposed above the lower limit of movement of the barb of the hook-needle, so that when the limbs of the thread-loop on the hook-needle are carried rearwardly by the feed of the work, such limbs are caused to straddle the loop-spreader which tends to wedge said limbs apart and spread open the loop.

As the point of the loop-spreader is much closer to the hook-needle than is the point of

the eye-needle, it follows that the loop-spreader enters the loop at a point closer to the base of the thread-triangle where the separation of the limbs of the thread-loop is greater. Also a greater shift of the last 70 stitch to one side of the plane of the needles is permissible without carrying the limbs of the loop to one side of the spreader point.

It is preferred to impart to the loop-spreader an upward movement early in the 75 up-stroke of the needles, to insure a full spread of the thread-loop at the shorter stitch-lengths and to hold the loop in the barb of the hook-needle until the loop is safely entered by the eye-pointed needle, thus 80 rendering unnecessary the close control of the thread-loop by the take-up, heretofore attained with difficulty.

The spreader-shank is adjustably mounted in the horizontal slot 22 in the spreader-carrier 23 which is pivotally mounted on the pin 24 fixed in the spaced lugs 25 on the under side of the bed-cover-plate 5. The pin 24 is mounted closely below the bed 5 so that the motion of the loop-spreader point 21 will, in its limited range of movement, be substantially vertical or in the direction of reciprocation of the needle.

The spreader-carrier 23 is formed with a vertical slot 26 in which is adjustably mounted the bar 27 having a hook-shaped lower end 28. The bar 27 extends between the spaced rollers 29 on the needle-bar head 8. The axes of the rollers 29 are diagonally spaced so that both the vertical and horizontal portions of the bar 27 are engaged by such rollers in the motion of the needle-bar. The pivot 24 is well to right, Fig. 2, of the vertical planes of the axes of the rollers 29, so that in the early upward movement of the needle-bar, the rollers 29 swing the spreader carrier 23 about its pivot 24 and impart an upward movement to the spreader-point 21. This movement of the spreader-point is faster than the movement of the needles and shifts the spreader 100 from the position shown in Fig. 10 to that shown in Fig. 13, thereby fully spreading the thread-loop for entry by the eye-needle 9. The spreader-blade 20 is formed below its point 21 with loop-lifting grooves 30, Fig. 17, 105 which engage the spread thread-loop and hold it in the barb of the hook-needle, Fig. 13, until the loop is safely entered by the eye-needle. The bar 27 is so shaped that its side edges are both substantially in engagement 110 with the rollers 29 at all times. When the loop-spreader reaches substantially the position shown in Fig. 13, it dwells while the needles continue their up-stroke; the rollers 29 working on the vertical portion of the 115 bar 27.

The lower limit of motion of the spreader 21 may be varied by adjusting the bar 27 higher or lower on the carrier 23. The point of the spreader 21 may be adjusted trans- 120

versely of the plane of the needles by shifting the spreader in the slot 22 of its carrier.

It is preferred to form the throat-plate 6 with a needle-hole or slot 31 which is closed at its sides and rear end 32, rather than opening into the feed-dog slot 33. Such a closed needle-slot limits the rearward slant of the thread-loop on the hook-needle when the feed is adjusted for the longer stitches. The needle-slot 31 also limits the side shift of the thread-loop when the last stitch is carried to one side of the plane of the needles by the feed of the work in sewing irregular seams or curved seams of short radius, as shown in Fig. 16. It is to be understood, however, that the closed needle-slot in the throat-plate is not essential to the invention in the broader aspects of the latter.

The use of the spreader in question renders it unnecessary to set the needles in parallelism with such a high degree of accuracy as heretofore. Furthermore, with the present spreader, a slightly bent needle will not cause the machine to skip.

Having thus set forth the nature of the invention what I claim herein is:

1. In a sewing machine, the combination with parallel hook and eye-pointed needles fixed relative to one-another and disposed in the vertical plane of seam-formation, of a loop-spreader having a flat triangular blade disposed in a plane transverse to the plane of said needles and having a loop-entering point extending in the same direction as the points of said needles.

2. In a sewing machine, the combination with hook and eye-pointed needles, of a thread-loop spreader having a loop-entering point and loop-engaging shoulders at opposite sides of said point.

3. In a sewing machine, the combination with hook and eye-pointed needles, of a thread-loop spreader having a loop-entering point and loop-engaging shoulders at opposite sides of said point, and means for reciprocating said spreader in the direction of reciprocation of said needles.

4. In a sewing machine, the combination with feeding mechanism, and a throat-plate having a needle-hole elongated in the direction of feed and having side and rear end walls, of reciprocating hook and eye-pointed needles fixed relative to one-another, and a loop-spreader disposed between said needles and at the same side of the throat-plate with said needles.

5. In a sewing machine, the combination with reciprocating hook and eye-pointed needles fixed relative to one-another, of a thread-loop spreader having a loop-entering point disposed between said needles and extending in the direction of reciprocation of said needles.

6. In a sewing machine, the combination with hook and eye-pointed reciprocating

needles fixed relative to one another, of a thread-loop spreader disposed between said needles, and means for moving said spreader in the direction of movement of said needles.

7. In a sewing machine, the combination with hook and eye-pointed reciprocating needles fixed relative to one-another, of a thread-loop spreader disposed between said needles, and means for moving said spreader in the direction of movement of said needles and faster than said needles.

8. In a sewing machine, in combination, hook and eye-pointed needles fixed relative to one-another, complementary loop-taking means, a needle-bar carrying said needles, and a loop-spreader actuated by said needle-bar and having a movement between and in the same direction as said needles.

9. In a sewing machine, the combination with hook and eye-pointed needles, of means moving with said needles in position to engage the thread-loop on the hook-needle before the needles enter the work and hold such loop in the barb of the hook-needle until said loop is safely entered by the eye-pointed needle.

10. In a sewing machine, the combination with hook and eye-pointed needles, a needle-bar carrying said needles, guides on said needle-bar spaced apart both vertically and horizontally, a loop-spreader, a spreader-carrier, and an actuator-bar connected to said spreader-carrier and having angularly related portions working between said guides.

11. In a sewing machine, the combination with hook and eye-pointed needles, a needle-bar carrying said needles, guides on said needle-bar spaced apart both vertically and horizontally, a loop-spreader, a spreader-carrier, and an actuator-bar connected to said spreader-carrier and having angularly related portions working between said guides, one of said portions being parallel with the needle-bar when engaged by said guides, thereby producing a dwell in the motion of the loop-spreader.

12. In a sewing machine, the combination with hook- and eye-pointed needles, and a needle-bar on which both of said needles are mounted in relatively fixed relation, of means engaging the thread-loop on the hook-needle between the hook-needle and the last stitch to spread such thread-loop for entry by the eye-pointed needle.

13. In a sewing machine, in combination, a throat-plate, stitch-forming mechanism including a needle-bar and hook-and eye-pointed needles mounted on said needle-bar below the throat-plate in relatively fixed relation, looper mechanism above the throat-plate and means below the throat-plate and in rear of the hook-needle for spreading the thread-loop on the hook-needle for entry by the eye-pointed needle.

14. In a sewing machine of the straw-

braid type, the combination with a reciprocating needle-bar, hook- and eye-pointed needles mounted on said needle-bar in relatively fixed relation, and cooperating looper mechanism, of means between said needles for spreading the thread-loop on the hook-needle for entry by the eye-pointed needle.

15. In a sewing machine, in combination, hook- and eye-pointed needles, a needle-bar on which said needles are mounted in relatively fixed relation, a throat-plate, a loop-spreader pivotally mounted closely below said throat-plate at a distance to one side of said needles, said loop-spreader having a loop-engaging portion disposed between said

10 needles and adapted to move in the direction of reciprocation of said needles, and means for actuating the loop-spreader in timed relation with said needles.

15 In testimony whereof, I have signed my name to this specification.

RUDOLPH BECKER.
